UNITED STATES PATENT OFFICE

RALPH P. HARLAN, OF CHICAGO, ILLINOIS

AUTOMATIC AIR TORPEDO

Application filed January 25, 1928. Serial No. 249,358.

My invention relates in general to toys. It relates more particularly to an improved type of automatic air torpedo cane by means of which a detonation-like sound is produced.

The invention is in many respects an improvement over the automatic air torpedo disclosed in Patent No. 1,004,043, issued September 26, 1911, to Otto A. Langos.

The principal object of the present invention is to provide an improved air torpedo of the type disclosed in the above mentioned patent.

Another object is to provide such an air torpedo which will be considerably less expensive to manufacture.

Another object is the provision of an air torpedo having a sturdy construction.

Another object is to improve the mechanism for feeding the paper ribbon.

Another object is to provide an air torpedo adapted to be operated either with a quick downward movement, or with a slow downward movement and a report produced in either instance.

Another object is to produce a greater compression of air and consequently a louder report than in the prior device.

Other objects and features of the invention will be apparent from a consideration of the detailed description taken with the accompanying drawings, wherein

Fig. 1 is an elevational view with the paper roll removed;

Fig. 2 is an elevational view at right angles to the view of Fig. 1 but with the roll in position for feeding;

Fig. 3 is a sectional view taken along the line 3—3 of Fig. 2 looking downwardly, and

Fig. 4 is a fragmentary vertical view taken along the line 4—4 of Fig. 3.

The automatic air torpedo mechanism is secured to any usual type of cane 10 having a special designed ferrule 11 with a cross pin 12 extending into slots 13 in a cylindrical portion 14 of a frame member 16. The frame member is suitably secured to the top of a cylinder 17 in which a suitable pump piston 18 is reciprocable. This piston is of the well-known removable

leather type so designed as to be substantially leak proof, and adapted to be repaired by renewing the leather or the like to maintain it in good workable condition. The pump piston has connected thereto, a piston rod 19 axially slidable in a cylinder cap 21, the piston rod or plunger 18 having a plunger cap 22 and being provided with a coil spring 23 having its ends engaging the cylinder cap 21 and plunger cap 22, respectively. This cap 22 is preferably made of live rubber to facilitate operation of the device and prevent slipping when the cane is pressed against the ground.

The special ferrule-like member 11 projects downwardly beyond the end of the cane 10 in the manner shown in Fig. 4, and has side openings 24 with an axial opening 26, the axial opening being adapted to fit over a corresponding opening in the top of the cylinder 17, this opening extends through a cylinder head 27 on which a live rubber washer 28 is set in the manner shown. The paper in strip or ribbon form, is adapted to be fed from a roll 29 along the top of the washer 28, and the end of the special ferrule engages the top side of the strip and clamps it against the rubber washer 28. This causes the paper tightly to seal the cylinder 17 so that on the pressure stroke of the piston, the air under pressure will be forced through the paper with a loud report.

In controlling the movement of the paper, the roll 29 is mounted on a spindle 31 which is bent at right angles and has a pivotal connection 32 to the frame 16. A latch 33 also pivoted to the frame has a spring bayonet slot into which the end of the spindle 31 is adapted to be snapped to prevent loss of the paper roll.

The paper strip is fed from the roll between the bottom of the special ferrule and across the top of the rubber washer 28, it being guided by the two sides or guide portions of the frame 16. For advancing the paper, a special mechanism is provided including a rack 36 pivotally secured to the cross pin 12, and having its bottom loosely secured in a guide 37 formed by partially exercising a portion of the frame and bending it out of the

normal plane thereof. The rack engages a ratchet wheel 38 and is pressed thereagainst by a light spring 39 in the manner shown in Fig. 3. The ratchet 38 is mounted on a transverse shaft 41 which is loosely held in the frame portion 16 in vertically extending slots 42. A feed wheel 43 is secured to the shaft in a position to engage against the paper strip, it being set slightly to one side thereof so as not to encounter the perforations blown in the paper by the pneumatic action of the plunger. Although the shaft is loose in the vertical slots, it is held in a downward position therein by a light leaf spring 44 which is secured to the cylinder portion 14 and extends in a U-shape so as to bear continuously against the shaft while still permitting ready turning thereof.

At the bottom of the frame 16, and secured thereto, is a bed plate 46 encircling the top of the cylinder and securing the same thereto so as to provide an integral structure. This plate furnishes the bed against which the feed wheel is pressed, and is smooth so as to facilitate the sliding of the paper strip. The farthest extending edge thereof, at the left hand side of Fig. 4, is finished in a straight edge so that when a sufficient quantity of the strip has been drawn across the bed plate, such strip may be pulled downwardly against the straight edge to sever itself at this point.

The cylinder head 27 is secured to the cylinder so as to comprise substantially a part thereof, but the rubber washer 28 is frictionally or adhesively secured in position so that it may be changed when worn without making it necessary to interfere with any of the other portions of the mechanism in any way whatsoever. An effective seal of the top of the cylinder by the paper is therefore always possible.

In the operation of the cane, the roll 29 is first applied in position on its support in the manner shown. The cane portion is held upwardly with respect to the frame, and the ribbon advanced between the bottom of the projecting end of the ferrule and the top of the bed plate so as to engage under the feed wheel 43.

50 The cane is now ready for use and the sequence of operation is as follows:

First the cane portion moves downwardly in the cylindrical portion 14 until the ferrule tip engages the paper around the edges of the axial opening in the washer 28. In so moving, the rack 36 turns the ratchet wheel 38 which in turn causes a rotary movement of the feed wheel and advances the ribbon across the bed plate. When the ferrule tip has engaged the rubber washer, further downward movement presses the plunger upwardly so that the consequent movement of the piston head compresses the air at the top of the cylinder until it is sufficiently great to break the paper seal. This is done with a loud re-

port not dissimilar to the ordinary torpedo report used by children during the July 4th period.

After each report, the cane is lifted upwardly, the first movement is a downward movement of the plunger due to the action of the spring 23. Toward the end of the plunger's travel, the weight of the air torpedo mechanism causes a movement thereof with respect to the cane 10. This draws the cross pin 12 upwardly in the slots 13 and the rack 36 drawn upwardly with respect to the ratchet wheel clicks over the teeth thereof until it assumes the position of Fig. 2 where it is all ready for another feeding stroke. This cycle of operations takes place each time the cane is "fired".

It is to be noted that the piston is adapted to travel to the extreme upper limits of the cylinder, and that consequently the air is compressed much more than when the spring is on the inside of the cylinder, and thus prevents the piston from having a full stroke.

Although I have described certain details of the present embodiment of my invention, it is not intended necessarily to restrict the invention to any specific form but it is limited only by the scope of the appended claims.

What I claim as new and desire to secure by United States Letters Patent is:

1. In an automatic air torpedo, a cane, a support in the cane for a roll of paper ribbon, an air pump mechanism for compressing a volume of air operable by downward pressure of the cane, means for holding the ribbon to be pierced by the action of the compressed air, a feed wheel near said holding means, and automatic means for turning the wheel to advance the ribbon before each operation of the pump mechanism and in the first movement of the cane as it is being pressed downwardly.

2. In an automatic air torpedo, a support for a roll of paper ribbon, an air pump mechanism for compressing a volume of air including a cylinder with an axial upper opening and a bed plate near said opening, means for holding the ribbon against said opening, to be pierced by the air when compressed, a feed wheel bearing against said bed plate and adapted to be turned to advance the ribbon along the bed plate, and means for turning the feed wheel before each operation of the pump mechanism and while the holding means is moving into holding position.

3. In an automatic air torpedo, a cane with a special ferrule at the end thereof, a frame member with a cylinder portion with vertical slots extending around the ferrule, a cross pin through the cane and ferrule and extending into the slots, a pump cylinder, a bed plate secured at the top of the cylinder and to the frame transversely thereof, the cylinder having an opening flush with said bed plate,

- 5 a piston reciprocable in the cylinder, and adapted to compress a volume of air, a support for a roll of paper ribbon, and means for drawing the ribbon across the bed plate to feed the same, the special ferrule having an extending portion adapted to engage the paper around the cylinder outlet to seal said outlet and permits sufficient compression of air within the cylinder to disrupt the paper.
- 10 4. In an automatic air torpedo, a cane, a specially designed ferrule at the end of the cane, with side openings in its projecting portion and an axial opening in the end thereof, a single piece frame including ribbon guiding portions and having cylinder portions engaging around the ferrule, a pin through the ferrule and extending into vertical slots in the cylindrical portion of the frame to limit the sliding movement between the cane and frame, a transverse bed plate secured across the guide portions of the frame, a pump cylinder having its upper end secured in the bed plate, a plunger in the cylinder adapted to be forced upwardly by engaging the bottom thereof against the ground, means for returning the plunger to unactuated position, a support for a roll of ribbon paper, and means for feeding the ribbon paper between the guides and across the bed plate.
- 15 20 25 30 35 40 45 50 55 60 65 70 75 80 85 90 95 100 105 110 115 120 125 130
- 5 a piston reciprocable in the cylinder, and adapted to compress a volume of air, a support for a roll of paper ribbon, and means for drawing the ribbon across the bed plate to feed the same, the special ferrule having an extending portion adapted to engage the paper around the cylinder outlet to seal said outlet and permits sufficient compression of air within the cylinder to disrupt the paper.
4. In an automatic air torpedo, a cane, a specially designed ferrule at the end of the cane, with side openings in its projecting portion and an axial opening in the end thereof, a single piece frame including ribbon guiding portions and having cylinder portions engaging around the ferrule, a pin through the ferrule and extending into vertical slots in the cylindrical portion of the frame to limit the sliding movement between the cane and frame, a transverse bed plate secured across the guide portions of the frame, a pump cylinder having its upper end secured in the bed plate, a plunger in the cylinder adapted to be forced upwardly by engaging the bottom thereof against the ground, means for returning the plunger to unactuated position, a support for a roll of ribbon paper, and means for feeding the ribbon paper between the guides and across the bed plate.
8. In an automatic air torpedo, a cane, a specially designed ferrule at the end of the cane, with side openings in its projecting portion and an axial opening in the end thereof, a single piece frame including ribbon guiding portions and having a cylindrical portion engaging around the ferrule, a pin through the ferrule and extending into vertical slots in the cylindrical portion of the frame to limit the sliding movement between the cane and frame, a transverse bed plate secured across the guide portions of the frame, a pump cylinder having its upper end secured in the bed plate, a plunger in the cylinder adapted to be forced upwardly by engaging the bottom thereof against the ground, means for returning the plunger to unactuated position, a support for a roll of ribbon paper, and means for feeding the ribbon paper between the guides and across the bed plate.
5. In an automatic air torpedo, a cane, a support for a roll of paper ribbon on the cane, an air pump mechanism carried by the cane in the lower end thereof for compressing a volume of air, said pump mechanism including a cylinder with an axial upper opening and a bed plate near said opening, means for holding the ribbon against the opening to be pierced by the air when compressed, a feed wheel resiliently held against the bed plate and adapted to be turned to advance the ribbon along the bed plate, and means for turning the feed wheel before each operation of the pump mechanism and while the holding means is moving into holding position.
6. In an automatic air torpedo, a cane, support for a roll of paper on the cane, an air pump mechanism carried by the cane at the lower end thereof for compressing a volume of air, said pump mechanism including a cylinder with an axial upper opening and a bed plate near said opening and flush with the top thereof, means for holding the ribbon against the opening to be pierced by the air when compressed, a feed wheel secured on a loosely mounted shaft spring pressed to engage the feed wheel against the bed plate, a ratchet wheel on the shaft and a spring pressed ratchet carried by the cane adapted to engage the ratchet wheel and turn the same as the ribbon holding means is moving into holding position.
7. In an automatic air torpedo, a cane, a specially designed ferrule at the end of the cane, with side openings in its projecting portion and an axial opening in the end there-
- of, a single piece frame including ribbon guiding portions and having a cylindrical portion engaging around the ferrule, a pin through the ferrule and extending into vertical slots in the cylindrical portion of the frame to limit the sliding movement between the cane and frame, a transverse bed plate secured across the guide portions of the frame, a pump cylinder having its upper end secured in the bed plate, a plunger in the cylinder adapted to be forced upwardly by engaging the bottom thereof against the ground, means for returning the plunger to unactuated position, a support for a roll of ribbon paper, and means for feeding the ribbon paper between the guides and across the bed plate.
9. In an automatic air torpedo, a cane, a specially designed ferrule at the end of the cane having an extending portion with side slots and a axial opening in the end thereof, a frame slidably connected with the ferrule and having a bed plate at the bottom thereof supporting an air cylinder, a sealing washer around the top of the cylinder and flush with the bed plate, a plunger in the cylinder projecting from the lower end thereof, a support for a roll of paper ribbon, and means for feeding the paper ribbon across the bed plate on the downward stroke of the cane as the ferrule is moving into position to seal the cylinder opening by holding said paper ribbon against said sealing washer.
10. In an automatic air torpedo, a cane, a

frame movable with respect to the lower end of the cane, a bed plate carried by the frame, an air cylinder extending into and held in an aperture in the bed plate, a transverse apertured partition in the cylinder near the top thereof, a sealing washer resting on the partition and extending to a position substantially flush with the bed plate, means for compressing the air in the cylinder, means for feeding a paper ribbon across the bed plate, and means for holding the paper ribbon in contact with said sealing washer as the air in the cylinder is compressed.

11. In an automatic air torpedo, a cane, a frame at the bottom of the cane having a pair of guides for a paper ribbon with a bed plate between the guides, an air pump mechanism below the bed plate, a shaft secured across the guides in vertical slots permitting slight vertical movement thereof, a spring tending to hold the shaft in the bottom of the slots, a feed wheel secured to the shaft between the guides and adapted to engage the ribbon, a ratchet wheel secured to the shaft on the outside of the guides, a ratchet wheel engaging rack pivoted at its upper end to the cane and a spring for pressing the rack against the ratchet wheel.

In witness whereof, I hereunto subscribe
my name this 28th day of December, 1927.
RALPH P. HARLAN.
